CLAIM

The ornamental design for a ceiling fixture, as shown and described.

DESCRIPTION

FIG. 1 is a bottom perspective view of a ceiling fixture showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines immediately adjacent the shaded areas represent the bounds of the claimed design while all other broken lines illustrate portions of the ceiling fixture; the broken lines form no part of the claimed design.

1 Claim, 7 Drawing Sheets(56)
